CLAIM

The ornamental design for a laundry ball, as shown and described.

DESCRIPTION

FIG. 1 is an isometric view of a laundry ball, in accordance with the design;

FIG. 2 is a right-side view of the laundry ball of FIG. 1;

FIG. 3 is a left-side view of the laundry ball of FIG. 1;

FIG. 4 is a front view of the laundry ball of FIG. 1;

FIG. 5 is a rear of the laundry ball of FIG. 1;

FIG. 6 is a top view of the laundry ball of FIG. 1; and,

FIG. 7 is a bottom view of the laundry ball of FIG. 1.

In the drawings, broken line areas illustrate environmental subject matter or boundaries that form no part of the claimed design.
